FIG. 1

FIG. 2

FIG. 3

FIG. 4

FIG. 5

FIG. 6

Fig. 1 is a perspective view of a slide viewer, showing my new design resting on its rear angle base;

Fig. 2 is a perspective view to a slightly larger scale, resting on its bottom base;

Fig. 3 is a side elevational view, the opposite side being substantially a mirror image thereof;

Fig. 4 is a bottom plan view;

Fig. 5 is a front elevational view; and

Fig. 6 is a top plan view thereof.

Portions of the drawing figures are diagonally lined to indicate transparency.

I claim:

The ornamental design for a slide viewer, as shown and described.
